UNITED STATES PATENT OFFICE.

WILLIAM R. PARK, OF TAUNTON, AND BELVIN T. WILLISTON, OF SOMERVILLE, MASSACHUSETTS, ASSIGNORS TO THE HANCOCK INSPIRATOR COMPANY, OF BOSTON, MASSACHUSETTS.

DESIGN FOR A CASING FOR BLANKS FOR DOUBLE OR COMPOSITE INJECTORS.

SPECIFICATION forming part of Design No. 32,501, dated April 10, 1900.

Application filed August 5, 1899. Serial No. 726,328. Term of patent 14 years.

To all whom it may concern:

Be it known that we, WILLIAM R. PARK, of Taunton, county of Bristol, and BELVIN T. WILLISTON, of Somerville, county of Middlesex, State of Massachusetts, have invented and produced a new and original Design for a Blank for a Casing of Double or Composite Injectors, of which the following is a specification, reference being had to the accompanying drawing, which forms a part hereof.

The drawings hereto annexed shows the blank for the casing for double or composite injectors which discloses the features of our design. These features are the block-shaped body B, from which projects the double barrel A. The body A approximates to a cube in

its proportions, and the barrel B, while substantially of the same width as the body A, is of considerably less depth.

What we claim, and desire to secure by Letters Patent, is the following:

The design for a blank for a casing for double or composite injectors, as herein shown and described.

Signed by us at Boston, Massachusetts, this 1st day of August, 1899.

WILLIAM R. PARK.
BELVIN T. WILLISTON.

Witnesses:

ROBERT CUSHMAN,
E. F. GROLL.
